SHUTTLE FOR NEEDLE LOOMS

Alva B. Byrem, Bloomsburg, Pa., assignor to
James Magee Webbing Company, Bloomsburg,
Pa., a corporation of Pennsylvania

Application May 10, 1933, Serial No. 670,340

16 Claims. (Cl. 139—124)

This invention relates to needle looms of the type disclosed in U. S. Letters Patent No. 1,797,962, dated March 24, 1931. In this particular type of loom a weft needle swings in a horizontal plane and passes a weft or filling thread through an open warp shed formed by two series of warp threads extending from the fell of the fabric in divergent relation to each other. The weft needle forms the filling thread into a loop beyond and at one side of the open warp shed and passes the loop around a relatively fixed shuttle which carries a binder or selvage thread through the filling loop to prevent the filling from being pulled out of the fabric from the opposite edge thereof during and subsequent to the reverse movement of the weft needle.

In the above noted patent, the binder shuttle is held in its substantially fixed position by and between a pair of relatively movable holding elements arranged to enter openings in the shuttle, and from which the holding elements are momentarily released during the advance or forward movement of the weft needle, to permit the passage of the filling loop around the shuttle, said holding elements being immediately reset to catch and hold the shuttle against displacement during the reverse movement of the weft needle.

The amount of clearance permissible to permit passage of the filling yarn around the shuttle, without losing control of the shuttle, is so slight in this type of loom that when jute or similarly rough and more or less shaggy and uneven yarns or threads are being used, such as in the production of upholstery webbing, loose fibers or small particles of such yarns, commonly referred to as "fly", become lodged in the holding openings of the shuttle and around the said relatively movable holding elements which are adapted to enter the said openings for the purpose above noted.

Such accumulation of fly prevents the filling loop from sliding freely over and around the shuttle, between the released holding elements and the shuttle. Thus, in many instances, the filling thread is pinched between the shuttle and the holding elements during the resetting thereof, after the thread theoretically has passed the points of contact therebetween, which results in the filling being broken or held in such a position as to prevent its being properly beat up at the fell of the fabric by the lay or reed of the loom.

The object of the present invention is to provide a shuttle for the type of loom above noted and a cradle and suitable cooperating mechanism for holding the shuttle in its substantially fixed position wherein delicate clearances which would

become readily clogged with fly are eliminated and wherein positively actuated relatively moving parts are likewise eliminated, to prevent pinching and consequent breaking of the filling yarn and whereby the said filling yarn may slide freely over and around the shuttle without being caught or retarded by an accumulation of fly at and around the shuttle-holding points.

The construction and operation of the mechanism forming the subject of the present invention will be fully disclosed hereinafter, reference being had to the accompanying drawings, of which:

Fig. 1 is a plan view of the improved shuttle and cradle mechanism with sufficient of the loom and the warp therein to illustrate the operation of the shuttle in accordance with the principles of the present invention;

Fig. 2 is a side elevation, partially in section as taken on the line 2—2, Fig. 1; and

Figs. 3 and 4 are respectively front and rear end elevations of the shuttle and cradle mechanism shown in Figs. 1 and 2.

As illustrated in Figs. 1 and 2, the shuttle comprises a body portion composed of a hollow cylindrical barrel element 2, in one end of which is secured an oblique conical nose piece 3, said nose piece being provided with a relatively sharply pointed end or vertex 4 eccentrically disposed with respect to the axis of the barrel 2.

In the opposite end the barrel 2 is secured a semi-elliptical tail piece 5 which is provided with a bluntly rounded end 6 disposed substantially in axial alignment with the barrel 2. The tail piece 5 is adapted to be readily removed from the barrel 2 for the purpose of gaining access to the interior of the shuttle, in view of which the tail piece 5 is provided with a circular end 7 of reduced diameter which fits within the barrel 2 snugly and provides a shoulder 8 adapted to abut firmly against the open end 9 of the hollow barrel 2. Secured in and extending laterally from the reduced neck 7 of the tail piece 5 is a pin 10 which is arranged to enter a bayonet slot 11 formed in and at the end of the barrel 2, whereby the nose piece 5 is firmly secured in the said otherwise open end 9 of the barrel 2.

The shuttle 1 is adapted to receive a bobbin or spool 15 on which is wound a selvage thread *a*, said selvedge thread passing out of the barrel 2, through an opening 16, and under a tension spring 17 provided at one end with a hook 18 fitting within an opening 19 formed in the barrel 2 of the shuttle 1, the opposite end of the resilient tension plate 17 being secured in place by

a screw 20 threaded into a boss 21 formed on the peripheral surface of the barrel 2 and between the outer face of which and the inner surface of the tension plate 17, and encircling the screw 20, 5 is a tension-regulating spring 22.

The shuttle 1 is adapted to be held in the relatively fixed position against longitudinal movement in either direction and against rolling or rotary movement about its axis, whereby the 10 point 4 of the nose 3 is at all times maintained above and in a vertical plane substantially coincident with the axis of the shuttle 1, while the tension plate 17 is maintained in a definite position at one side of the shuttle and the cradle 15 mechanisms by which the shuttle is supported.

The cradle mechanism comprises a horizontally disposed base plate 25 provided with wings 26, 26 adapted to be secured to a fixed portion 28 of the loom by bolts 29, 29 respectively. One end 20 of the base plate 25 is provided with a central forwardly extending inclined ear 30, against which the longer lower lateral surface of the oblique conical nose piece 3 is adapted to rest, said ear 30 acting as an elevator to raise the point 25 4 of the nose 3 at all times.

The extremity or lobe 32 of the ear 30 is bent downwardly to form, together with the point 4, and lower surface of the nose 3, a throat 33 for receiving the filling thread as will be hereinafter 30 described.

At one side of the shuttle 1 and extending in a general vertical direction up and around one side of the oblique conical nose 3 is a horn 35 which prevents lateral movement of the nose end of the 35 shuttle in one direction horizontally and also functions as a guide for the filling thread *b* as will be hereinafter described.

Lateral movement of the nose end of the shuttle in an opposite horizontal direction, and lateral 40 movement of the shuttle as a whole in said direction, is prevented by a rib 36 formed on the base plate 25 and extending along and substantially throughout the length of the barrel 2 of the shuttle 1 in a direction substantially parallel to 45 the said barrel of the shuttle.

Lateral movement of the tail end of the shuttle in the first said horizontal direction is prevented by a lug or projection 37, in the present instance composed of a bent wire secured to the base plate 50 25 by a screw 38.

Vertical displacement of the nose end of the shuttle 1 is prevented by an adjustable stop 40 which, in the present instance, is in the form of a headed screw 41 threaded into an arm 42 which 55 extends substantially parallel to and in a position spaced above the barrel 2 of the shuttle 1.

Rolling or rotary movement of the shuttle 1 is prevented by a tongue 45 which, in the present instance, is pivotally mounted, at one of its ends, 60 on a pin 44 carried by the pair of spaced parallel and depending lugs 43 formed on the arm 42 at the opposite end thereof from the vertical stop 40. The tongue 45 extends lengthwise of the barrel of the shuttle and is inclined from its pivot 65 end toward the said body of the shuttle with a goodly portion of its length including its free end disposed in a substantially U-shaped groove or socket 50 formed in the top surface of the barrel 2.

The socket 50 is formed by a pair of ribs 49, 49 which toward the center of the length of the barrel 2 are substantially parallel to each other, to receive the tongue 45. Toward the tail end of the shuttle the ribs 49, 49 flare outwardly as 70 indicated at 48, 48 in Fig. 1. The ribs 49, 49, are

connected, substantially at the center of the barrel 2, by a transversely extending rib 47 which forms an abutment in the groove or socket 50 which is engaged by a lip 46 formed on the said free end of the tongue 45, whereby longitudinal 5 rearward movement of the shuttle, in and relative to the cradle, is effectively prevented.

The tongue 45 is resiliently held in the socket 50 of the shuttle 1 by means of a spring 51 disposed between the upper side of said tongue and the lower side of the arm 42. The free end of the tongue, however, is held out of engagement with the base of the socket 50 by the heel 53 of the said tongue engaging the end of the supporting arm 42, to permit the filling thread *b* to slide 15 freely between the tongue 45 and the end and side walls and the base of the socket 50, as will be hereinafter described.

The arm 42 is provided with a vertically extending stud 55 which passes through a slot 56 20 formed in a transversely extending arm 57, said stud 55 being threaded and provided with jam nuts 58, 58 by which the arm 42 is clamped to the arm 57 in alignment with the shuttle 1.

The arm 57 is pivotally mounted at 59 on the 25 upper end of a post 60 which projects vertically from a lateral extension 61 of the base plate 25. Secured to the post 60 is a segmental plate 62 which is provided with an opening 63 adapted to receive the lower end 64 of a spring-pressed 30 plunger 65. The spring-pressed plunger 65 is slidably mounted, for vertical movement, in the arm 57 and in an inverted cup 66 which is secured to the upper side of the arm 57 by screws 67, 67. A spring 68 encircles the plunger 65 between the 35 base of the cup 66 and an annular flange 69 formed on the said plunger 65. The plunger 65, above the cup 66, is provided with a head or knob 70, by which the lower end 64 of the plunger may be drawn upwardly out of the opening 63 40 in the plate 62, permitting the arm 57 to be swung about its pivot 59 for moving the arm 42 and tongue 45 out of their normal positions with respect to the shuttle 1, whereby the shuttle 1 may be readily removed from its supporting cradle. 45

The arm 57 is adapted to be swung in an opposite direction by a spring 71 having one end 72 secured in the post 60 and its opposite end 73 anchored in a depending lug or post 74 carried by the arm 57, a stop pin 75 being provided on 50 the plate 62 to prevent a swinging of the arm 57 beyond the point at which the arm 42 is substantially aligned with the shuttle 1.

The weft needle of the loom, shown in Fig. 1 and indicated at 100, is in the form of a rod bent on an arc having a radius struck from the point about which the said needle swings in a horizontal plane, as clearly illustrated in the above noted patent. 55

Adjacent its extreme free end 99, the arcuate needle 100 is provided with an eye 98 through which the filling thread *b* passes, the said filling thread being attached to one edge of the fabric *c* and extending through the open warp shed and from the fell of the fabric at the opposite edge thereof as indicated at the point *c*¹, said thread then extending from the said point *c*¹ to the eyelet 98, thence through an opening 97 in the needle 100 to a second eyelet 96 carried thereby and from which the said thread extends to and through a third eyelet 95 carried by the needle 100, from which the said thread extends in a horizontal plane through the open warp shed *c*², to a guide (not shown) at the bar side of the warp. 60 65 70 75 75

In the course of weaving of the fabric *c*, the weft or filling thread *b*, when the needle 100 is withdrawn and the point 99 thereof is disposed adjacent the opposite side of the fabric *c* from that shown in Fig. 1 of the present drawings, extends from the fell of the fabric at the said opposite side of the fabric to the eyelet 98 in the end of said needle. As the needle advances through the open warp shed the thread *b* is carried into the said open warp shed from the far side thereof by the eyelet 98 of the needle 100 until the portion *b*¹ of the thread assumes substantially the position at the fell of the fabric as illustrated in the present drawings and in so doing the portion *b*² of the thread *b*, stretched tautly between the fell of the fabric and the eyelet 98, is swung in a horizontal plane about the point of attachment of the thread to the fabric until the portion of the thread adjacent the eyelet 98 is disposed beyond the edge of the fabric *c* as shown in Fig. 1 of the drawings.

Due to the horizontal plane of the needle being disposed above the horizontal axis of the shuttle 1 the portion *b*² of the thread, during the said swinging action, first engages the tail 5 of the shuttle above the blunt point 6 thereof and rides up over the surface *d* of the said tail, thence into the mouth *e* between the upper surface of the shuttle 1 and the lower surfaces of the tongue 45 and the lugs 43 in which the said tongue is pivotally mounted.

Continued movement of the needle causes the thread to slide over the upper edges *f* of the ribs 49 and under the bottom surface *g* of the tongue 45, thence around the end of the tongue 45 between the surface *h* thereof and the surface *i* of the transverse rib or abutment 47, the relatively loose mounting of the shuttle in the cradle permitting slight forward longitudinal movement of the shuttle in the cradle to permit the thread to slip through between the surfaces *h* and *i* and to come to rest on the upper surface *j* of the barrel 2. The said thread then slides under the lower surface *k* of the vertical stop 40, and down the upper surface *l* of the conical nose 3 of the shuttle.

As the needle assumes or approaches the position relative to the shuttle 1 as shown in Fig. 1, the portion *b*² of the thread *b* snaps over the point 4 of the nose 3 of the shuttle and drops below said point as clearly illustrated in Fig. 2, the said thread being then in contact with the horn 35 which bends the former straight section *b*² of the thread into two angularly disposed sections *b*³ and *b*⁴ which extend respectively from the eye 98 and point *c*¹ of the fabric *c* toward and around the horn 35.

Reverse movement of the needle 100, in the direction of the arrow shown in Fig. 1, causes the portion *b*³ of the thread to pass into the throat 33 (see Fig. 2) between the upper surface *m* of the ear 30 and the bottom surface *n* of the nose 3, said portion of the thread sliding down and between said surfaces and between the inner surface *o* of the horn 35 and the side surface *p* of the nose 3, thence along and under the bottom of the shuttle between the lower surface *q* thereof, the upper surface *r* of the base plate 25 and the edge surface *w* of the longitudinal rib 36 of said base plate.

The end 99 of the needle then recedes to a position within the open warp shed *c*² and the thread is drawn from between the lower surface *q* of the shuttle 1, the upper surface *r* of the base plate 25 and the surfaces *s* and *t* of the rib 36

and guide 37 respectively and around the lower surface *n* of the tail 5, the said thread then slipping over and off the upper surface *v* of the shuttle guide 37.

In the course of travel of the thread *b* as described the said filling thread has been carried around the selvedge thread *a* which extends from the shuttle 1 to the point *c*¹ along the edge of the fabric *c*, as clearly illustrated in Fig. 1.

Continued retractive movement of the needle 100 draws the portion of the thread shown in broken lines in Fig. 1 down into the open warp shed to the fell of the fabric in substantially parallel relation to the portion *b*¹ of the thread previously laid at the fell of the fabric, or substantially so, the filling thread *b* being wrapped or looped around the selvedge thread *a* as illustrated at *a*¹ in Fig. 1, which prevents the parallel adjacently disposed portions of the double shot of filling thread from being drawn out of the fabric.

From the above description taken in connection with the drawings, it will be quite obvious that while the shuttle is held in a substantially fixed position the mounting is such that considerable freedom is provided between the shuttle, the cradle, and the other retaining elements which permits free easy sliding of the filling thread around the shuttle and avoids the necessity of delicate adjustments, close clearances and positively actuated parts which would easily become clogged with fly or which would pinch the thread in event of its being retarded by an accumulation of fly.

I claim:

1. In a loom provided with a weft needle operable in a horizontal plane for carrying a filling thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle for loosely supporting the shuttle in said position in the path of the loop carried by the needle, and means above and engaging the center of the cylindrical portion of the shuttle longitudinally and transversely thereof for preventing rolling of the shuttle in the cradle and for allowing the shuttle to rock longitudinally as the filling thread passes between the shuttle and the cradle.

2. In a loom provided with a weft needle operable in a horizontal plane for carrying a filling thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle for loosely supporting the shuttle in the path of the loop carried by the needle, and means cooperating with the underside of the said nose of the shuttle for directing the thread under the shuttle.

3. In a loom provided with a weft needle operable in a horizontal plane for carrying a filling thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle

for loosely supporting the shuttle in the path of the loop carried by the needle including an inclined ear engaging the smooth outer surface of the longer underside of the nose to hold said nose 5 upwardly in the cradle and for limiting forward longitudinal movement of the shuttle in the cradle.

4. In a loom provided with a weft needle operable in a horizontal plane for carrying a filling 10 thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle for loosely supporting the shuttle in the path of the loop carried by the needle including an inclined ear engaging the smooth outer surface of the longer underside of the nose to hold said nose 15 upwardly in the cradle and for limiting forward longitudinal movement of the shuttle in the cradle, and a lobe on said ear bent outwardly from and disposed in divergent relation to the said underside of said nose and cooperating therewith to direct the thread under the shuttle.

5. In a loom provided with a weft needle operable in a horizontal plane for carrying a filling 20 thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle for loosely supporting the shuttle in said position in the path of the loop carried by the needle, comprising a relatively flat base on which rests the cylindrical portion of the shuttle, an inclined 25 ear projecting from one end of said base and engaging the smooth outer surface of the longer underside of the nose of the shuttle to hold said nose upwardly in the cradle and for limiting forward longitudinal movement of the shuttle in the cradle, and means for limiting longitudinal movement of the shuttle in an opposite direction in the cradle.

6. In a loom provided with a weft needle operable in a horizontal plane for carrying a filling 30 thread as a loop through and beyond an open warp shed in the loom, a substantially cylindrical shuttle disposed with its axis substantially parallel to and below the plane of movement of the needle and loop carried thereby, an oblique conical nose piece at one end of the shuttle with its vertex above the plane of the needle, a cradle for loosely supporting the shuttle in said position in the path of the loop carried by the needle, comprising a relatively flat base on which the cylindrical portion of the shuttle rests, an inclined ear projecting from one end of said base and engaging the smooth outer surface of the longer underside of the nose of the shuttle to hold said nose upwardly in the cradle and for limiting forward longitudinal movement of the shuttle in the cradle, means for limiting longitudinal movement of the shuttle in an opposite direction in the cradle, and means for limiting vertical movement of the nose of said shuttle relative to the 35 ear of the cradle.

7. In a loom provided with a weft needle operable in a horizontal plane for carrying a filling 40 thread as a loop through and beyond an open warp shed in the loom, a substantially cylindrical shuttle disposed with its axis substantially parallel to and below the plane of movement of the needle and loop carried thereby, a tail piece having a pointed end below the plane of the needle at one end of the shuttle, an oblique conical nose piece at the opposite end of the shuttle with its vertex above the plane of the needle, a cradle for loosely supporting the shuttle in said position in the path of the loop carried by the needle, comprising a relatively flat base on which the cylindrical portion of the shuttle rests, an inclined ear projecting from one end of said base and engaging the smooth outer surface of the longer underside of the nose to hold said nose upwardly in the cradle and for limiting forward longitudinal movement of the shuttle in the cradle, means for limiting longitudinal movement of the shuttle in an opposite direction in the cradle, means for limiting vertical movement of the shuttle relative to the cradle, and means for preventing rotation of the shuttle in the cradle.

8. In a loom provided with a weft needle operable in a horizontal plane for carrying a filling 45 thread as a loop through and beyond an open warp shed in the loom, a substantially cylindrical shuttle having oppositely pointed ends disposed respectively above and below the plane of movement of the needle and loop carried thereby, a cradle for loosely supporting the shuttle in said position in the path of the loop carried by the needle, and a resilient element disposed in fixed 50 relation to the cradle and having one end disposed substantially at the center longitudinally and transversely of the cylindrical position of the shuttle in a socket formed in the shuttle to prevent rolling of the shuttle in the cradle while permitting free passage of the thread along the shuttle and a consequent longitudinal rocking of the shuttle in the cradle.

9. In a loom provided with a weft needle operable in a horizontal plane for carrying a filling 55 thread as a loop through and beyond an open warp shed in the loom, a substantially cylindrical shuttle having oppositely pointed ends respectively disposed above and below the plane of movement of the needle and loop carried thereby, a cradle loosely supporting the shuttle in said position in the path of the loop carried by the needle, and a resilient tongue disposed at one of its ends in fixed relation to the cradle above the shuttle with its opposite end disposed substantially at the center longitudinally and transversely of the cylindrical position of the shuttle in a socket formed in the upper surface of the shuttle and adapted to engage the end and side walls of the socket to prevent rolling of the shuttle in the cradle and to limit longitudinal movement of the shuttle in the cradle in one direction while permitting free passage of the thread along the shuttle and a consequent longitudinal rocking of the shuttle in the cradle in the opposite direction.

10. In a loom provided with a weft needle operable in a horizontal plane for carrying a filling 60 thread as a loop through and beyond an open warp shed in the loom, a substantially cylindrical shuttle having opposite pointed ends disposed respectively above and below the plane of movement of the needle and loop carried thereby, a cradle loosely supporting the shuttle in said position in the path of the loop carried by the needle, a retaining tongue disposed above the shuttle with one end thereof disposed substantially at the center longitudinally and transversely of the cylindrical portion of the shuttle in a socket formed in the upper surface of the shuttle, means for pivotally mounting the op-

- posite end of said tongue in fixed relation to the cradle, and means for resiliently pressing the tongue into the socket for allowing longitudinal rocking of the shuttle in the cradle and free passage of the thread between the shuttle and the tongue while retaining the shuttle against circular and longitudinal shifting in the cradle.
11. In a loom provided with a weft needle operable in a horizontal plane for carrying a filling thread as a loop through and beyond an open warp shed in the loom, a substantially cylindrical shuttle having oppositely pointed ends respectively disposed with its axis above and below the plane of movement of the needle and loop carried thereby, a cradle loosely supporting the shuttle in said position in the path of the loop carried by the needle, an arm fixedly supported above and in spaced relation to the shuttle, a resilient tongue mounted at one end on said arm with the opposite end of the tongue disposed in a socket formed in the upper surface of the shuttle, and means for pivotally mounting the said arm for swinging said tongue out of said relation to the shuttle to permit removal of the shuttle from the cradle.
12. In a loom provided with a weft needle operable in a horizontal plane for carrying a filling thread as a loop through and beyond an open warp shed in the loom, a substantially cylindrical shuttle having oppositely pointed ends respectively disposed with its axis above and below the plane of movement of the needle and loop carried thereby, a cradle loosely supporting the shuttle in said position in the path of the loop carried by the needle, an arm fixedly supported above and in spaced relation to the shuttle, a resilient tongue mounted above the shuttle with a portion thereof disposed in a socket formed in the upper surface of the shuttle to prevent rolling of the shuttle in the cradle, to limit rearward longitudinal movement of the shuttle in the cradle and permitting free passage of the thread along and around the shuttle and between the shuttle and the resilient tongue.
13. In a loom provided with a weft needle operable in a horizontal plane for carrying a filling thread as a loop through and beyond an open warp shed in the loom, a substantially cylindrical shuttle disposed with its axis substantially parallel to and below the plane of movement of the needle and loop carried thereby, a tail piece having a pointed end below the plane of the needle at one end of the shuttle, an oblique conical nose piece at the opposite end of the shuttle with its vertex above the plane of the needle, a cradle for loosely supporting the shuttle in said position in the path of the loop carried by the needle, comprising a relatively flat base on which the cylindrical shuttle rests, a rib on said base and extending longitudinally of the shuttle for preventing lateral movement of the shuttle as a whole in one transverse direction in the cradle, a horn adjacent the nose end of the shuttle to limit lateral movement thereof in the opposite transverse direction, a lug on said base adjacent the said opposite side of said tail piece to limit lateral movement thereof in said opposite transverse direction, an inclined ear projecting from said base to be engaged by the underside of the nose for limiting forward longitudinal movement of the shuttle in the cradle, and a resilient tongue mounted above the shuttle with a portion thereof disposed in a socket formed in the upper surface of the shuttle to prevent rolling of the shuttle in the cradle, to limit rearward longitudinal movement of the shuttle in the cradle and permitting free passage of the thread along and around the shuttle and between the shuttle and the resilient tongue.
14. In a loom provided with a weft needle operable in a horizontal plane for carrying a filling
15. In a loom provided with a weft needle operable in a horizontal plane for carrying a filling thread as a loop through and beyond an open warp shed in the loom, a substantially cylindrical shuttle disposed with its axis substantially parallel to and below the plane of movement of the needle and loop carried thereby, a tail piece having a pointed end below the plane of the needle at one end of the shuttle, an oblique conical nose piece at the opposite end of the shuttle with its vertex above the plane of the needle, a cradle for loosely supporting the shuttle in said position in the path of the loop carried by the needle, comprising a relatively flat base on which the cylindrical shuttle rests, a rib on said base and extending longitudinally of the shuttle for preventing lateral movement of the shuttle as a whole in one transverse direction in the cradle, a horn adjacent the nose end of the shuttle to limit lateral movement thereof in the opposite transverse direction, a lug on said base adjacent the said opposite side of said tail piece to limit lateral movement thereof in said opposite transverse direction, an inclined ear projecting from said base to be engaged by the underside of the nose for limiting forward longitudinal movement of the shuttle in the cradle, an abutment spaced above the nose end of the shuttle to limit vertical movement thereof relative to said ear, and a resilient tongue mounted above the shuttle with a portion thereof disposed in a socket formed in the upper surface of the shuttle to prevent rolling of the shuttle in the cradle, to limit rearward longitudinal movement of the shuttle in the cradle and permitting free passage of the thread along and around the shuttle and between the shuttle and the resilient tongue.
16. In a loom provided with a weft needle operable in a horizontal plane for carrying a filling thread as a loop through and beyond an open warp shed in the loom, a substantially cylindrical shuttle disposed with its axis substantially

parallel to and below the plane of movement of the needle and loop carried thereby, a tail piece having a pointed end below the plane of the needle at one end of the shuttle, an oblique conical nose piece at the opposite end of the shuttle with its vertex above the plane of the needle, a cradle for loosely supporting the shuttle in said position in the path of the loop carried by the needle, comprising a relatively flat base on which the cylindrical shuttle rests, a rib on said base and extending longitudinally of the shuttle for preventing lateral movement of the shuttle as a whole in one transverse direction in the cradle, a horn adjacent the nose end of the shuttle to limit lateral movement thereof in the opposite transverse direction, a lug on said base adjacent the said opposite side of said tail piece to limit lateral movement thereof in said opposite transverse direction, an inclined ear projecting from said base to be engaged by the underside of the nose for limiting forward longitudinal movement of the shuttle in the cradle, an abutment spaced

above the nose end of the shuttle to limit vertical movement thereof relative to said ear, a resilient tongue mounted above the shuttle with a portion thereof disposed in a socket formed in the upper surface of the shuttle to prevent rolling of the shuttle in the cradle, to limit rearward longitudinal movement of the shuttle in the cradle and permitting free passage of the thread along and around the shuttle and between the shuttle and the resilient tongue, an arm extending substantially parallel to the shuttle and supporting said abutment and said tongues at its opposite ends respectively, a second arm pivotally mounted on said base and extending transversely to said shuttle for adjustably supporting said first arm, resilient means for swinging said second arm about its pivot to bring said abutment and tongue into operative relation to the shuttle, and means for securing said second arm in said position.
